UNITED STATES PATENT OFFICE.

JOHN T. SHEILS, OF SYRACUSE, NEW YORK.

HAME.

SPECIFICATION forming part of Letters Patent No. 674,387, dated May 21, 1901.

Application filed May 14, 1900. Serial No. 16,600. (No model.)

To all whom it may concern:

Be it known that I, JOHN T. SHEILS, a citizen of the United States, and a resident of Syracuse, in the county of Onondaga, in the State of New York, have invented new and useful Improvements in Hames, of which the following, taken in connection with the accompanying drawings, is a full, clear, and exact description.

10 This invention relates to the class of hames which are formed of metal tubes.

The invention consists in an improved construction of the body of the hame and the usual appurtenances—viz., the tug loop or 15 staple and the terret loop or ring—as herein-after described, and set forth in the claims.

The invention is fully illustrated in the annexed drawings, in which—

Figure 1 is a front view of a hame embodying my invention, portions being broken away to show the attachment of the terret loop or ring. Fig. 2 is an enlarged transverse section on line X X in Fig. 1. Fig. 3 is an enlarged longitudinal section of the portion of 25 the hame to which the tug-loop is attached. Fig. 4 is a detached front view of a tug-loop designed for a single harness. Fig. 5 is a longitudinal section of the lower end portion of the hame, showing the construction of the eye 30 for the lower strap-loop; and Fig. 6 illustrates a modification of my invention.

A represents the hame-body, which is formed of a metal tube and has its inner wall formed with a flat face *a*, extending lengthwise of the main portion of the hame.

B represents the longitudinal reinforcing-rod, which is half-round or segmental in cross-section and rests with its flat side *b* on the flat face *a* of the hame and is rigidly fastened 40 to the hame by means of rivets *a'*. Said rod serves, in addition to its reinforcing the hame, to also form a rib by which the hame obtains a secure hold in the usual crease formed in the front of the collar by the projecting welt thereof.

The lower end portion of the hame is flattened and bent into the shape of an eye *b'* and terminated with a tongue *c*, which laps onto the adjacent flattened part of the hame, 45 as shown more clearly in Fig. 5 of the drawings. In the eye *b'* is pivoted the usual lower strap-loop *c'*. The lower end of the reinforce-

ing-rod *B* laps onto the tongue *c* and is preferably formed with an offset *d* for the reception under it of the tongue *c* and to form a 55 close and neat joint therewith. A rivet *d'* passes through said joint and flattened portion of the hame and permanently unites said parts thereat.

C represents the so-called “tug-staple,” 60 which in my present invention consists of a loop projecting rigidly from a stay-plate *e* and preferably formed in one piece therewith. From the upper end of the plate *e* projects a hook-shaped tongue *e'*, which is inserted 65 through a perforation *f* in the outer wall of the hame-body and extends upward at the interior of the hame to obtain a secure hold therein. The lower end of the plate *e* is provided with an aperture or eye *f'*, which coincides with perforations *g* and *g'* in the hame-body and in the reinforcing-rod *B*. A bolt *h*, passing through said eye and perforations, fastens the lower end portion of the plate *e* 70 securely to the exterior of the hame and confines the hook-shaped tongue *e'* in its engagement with the interior of the hame. The head of the bolt is countersunk to obviate its cutting or otherwise injuring the collar to 75 which the hame is applied.

The curved bar which constitutes the tug-loop *C* is formed with a vertical eye *i*, in which is hung the holdback-ring *D*. When the tug-loop is designed to be applied to the hame of a single harness, said loop is formed without the aforesaid eye, as shown in Fig. 4 of the drawings.

E denotes the terret, consisting of an eye or loop through which the rein passes. When said terret is to be rigid on the hame, said eye 90 or loop is formed with a hook-shaped tongue *h'*, which is inserted through a perforation *i'* in the outer wall of the hame and terminated with an upward extension at the interior of the hame substantially in the same manner 95 as the tongue *e'* on the stay-plate of the tug-loop hereinbefore described. A bracing-arm *j* extends downward from the eye or loop *E* and bears with its lower end on the exterior of the hame and is firmly secured thereto by 100 means of a bolt or rivet passing through said end of the arm *j* and through the hame and rod *B*.

When the terret *E* is to be pivoted, I em-

ploy a stay-plate b^2 , which rests on the exterior of the hame and is secured thereto by a hook-shaped tongue h' , entering the interior of the hame through a perforation i' in the 5 hame, and by a bolt a^2 , passing through the lower portion of the plate b^2 and through the hame A and rod B in substantially the same manner as the attachment of the stay-plate e of the tug-loop.

10 The plate b^2 has projecting from it two perforated ears c^2 , between which is pivoted a lug formed on the eye or loop E, as shown in Fig. 6 of the drawings.

15 One of the great advantages of my invention is the facility afforded for repairing or renewing the tug-loop and the terret on the hame.

What I claim as my invention is—

1. A hame-body having its lower end portion formed with an eye and terminated with a tongue lapping onto the inner face of the body, a loop pivoted in said eye, a reinforcing-rod secured to the aforesaid face of the body and having its lower end lapped onto 25 the aforesaid tongue, and a rivet passing through said rod, tongue and hame-body as set forth.

2. A hame-body composed of a metal tube formed with a flat inner face, the lower end 30 portion of the body formed with an eye and terminated with a tongue lapping onto the

aforesaid face, the strap-loop pivoted in said eye, a reinforcing-rod secured to the flattened portion of the hame-body and formed with a correspondingly-flattened bearing and having its lower end lapping onto the aforesaid tongue, and a rivet passing through said rod, hame-body and intervening tongue as set forth. 35

3. The combination of a hame composed of 40 a metallic tube provided with perforations, a plate seated on the exterior of the hame and formed with a hook-shaped tongue passing through one of said perforations and engaging the interior of the hame, a bolt or rivet 45 fastening said plate in position, and a loop projecting from said plate as set forth.

4. The combination of a tubular hame, provided on its inner face with a longitudinal reinforcing-rod and with a perforation in its 50 outer wall, a plate seated on the exterior of the hame and provided with a hook-shaped tongue passing through said perforation and engaging the interior of the hame, a bolt passing through said plate, hame, and reinforcing-rod, and a loop projecting from said plate as 55 set forth and shown.

JOHN T. SHEILS.
